Attorney.

UNITED STATES PATENT OFFICE.

THOMAS UTLEY, OF LIVERPOOL, ENGLAND.

SHIP'S VENTILATOR.

SPECIFICATION forming part of Letters Patent No. 461,694, dated October 20, 1891.

Application filed June 3, 1891. Serial No. 394,950. (No model.) Patented in England June 5, 1890, No. 8,729.

To all whom it may concern:

Be it known that I, THOMAS UTLEY, engineer, a subject of the Queen of Great Britain, and a resident of Stoneycroft, Liverpool, England, have invented certain new and useful Improvements in and Relating to Ships' Ventilators, (for which I have obtained a patent in Great Britain, No. 8,729, and dated June 5, 1890,) of which the following is a specification, reference being had to the accompanying drawings.

My invention relates to ships' ventilators, and is designed to afford the means whereby a large supply of air may be admitted to a cabin, hold, or other compartment of a ship in fine weather, while the ingress of water through the ventilator in rough or stormy weather can be effectually prevented without the necessity for the removal or unshipping of any portion of the said ventilator. For this purpose I construct or provide the ventilator with an adjustable cowl having a suitable door or shutter whereby the mouth or aperture thereof may be easily closed in stormy or wet weather to prevent the entrance of water, and I provide suitable means whereby a tight joint may be made between the said cowl and the ventilating pipe or passage. My improved cowl therefore does not require to be removed or unshipped in stormy weather, as is the case with the ordinary deck ventilating-cowls.

In the accompanying drawings I have shown how my said invention may be conveniently and advantageously carried into practice.

Figure 1 represents in vertical central section one form of my improved ventilator. Fig. 2 is a similar view showing another form or modification of my invention and illustrating the application thereof to an ordinary or existing cowl-coaming.

Like letters indicate corresponding parts in these two figures.

A is a ventilating-pipe. B is a cowl, which is supported over the upper end of the said pipe A in such a manner that it can be turned into any desired position so as to effectually catch the wind. C is a shutter or door adapted to close the mouth or aperture of the said cowl. An annular groove or recess A* is formed in the upper part A'

of the ventilating-pipe A, in which groove or recess is inserted a ring or washer E, of india-rubber or other suitable packing.

The cowl B is provided with an internal 55 flange D. In the apparatus shown in Fig. 1 this flange is formed with an annular groove or recess D', in which is fitted a ring or washer E', of india-rubber or other suitable packing. The upper edge A² of the ventilating-pipe 60 enters the said recess D', and the lower edge B' of the cowl B enters the recess A*, so that by pressing or screwing down the cowl B, as hereinafter described, upon the top of the said ventilating-pipe the said packing-rings 65 E E' are compressed, and a water-tight joint is thus formed around the said cowl between the same and the ventilating-pipe. To provide for so pressing down the cowl upon the ventilating-pipe A, I employ a screw F, firmly 70 fixed in the one part—for example, the cowl—and fitting into a tapped hole in the other part.

In the apparatus shown in Fig. 1 the cowl B is provided with a cross-bar or cross-piece 75 G, and in the top of the ventilating-pipe A is provided a cross-bar or cross-piece H. The screw F is provided with a reduced screw-threaded portion F', which fits into a correspondingly screw-threaded hole in the cross-bar G or in a boss G', formed thereon, and the said screw is firmly secured and retained in position in the said cross-bar by means of a collar F² and lock-nut G². I provide, moreover, a tapped or screw-threaded hole in a 85 boss or nut H' on the cross-bar or cross-piece H, into which the screw F is inserted, so that the axis of the said screw corresponds with the axis of rotation of the cowl. Therefore by turning the cowl B in one direction the 90 screw F will be caused to turn in the boss or fixed nut H', and thus draw the said cowl tightly down upon the ventilating-pipe, while by turning the said cowl in the reverse direction it may be released to permit of its being 95 turned or adjusted to catch the wind. Moreover, the cowl can by this arrangement be very readily removed and replaced, if necessary, at any time.

The shutter or door C is imperforate and 100 pivoted or hinged at I to lugs J, secured to or formed on the cowl B.

C' is an annular recess formed around the inner face of the shutter or door C and adapted to receive a ring C², of suitable packing, for forming a water-tight joint between the said 5 shutter or door and the adjacent edge of the cowl.

K is a bolt pivoted at K' to lugs K² upon the cowl B and adapted to enter a suitable slot in an extension C³ of the shutter C.

10 L is a nut which is screwed upon the bolt K, to constitute a clamp by means of which the shutter or door C can be firmly clamped or secured in its closed position. Any other suitable fastening device may, however, be 15 provided that will admit of the said shutter or door being opened and thrown back to uncover the aperture or mouth of the cowl and of its being securely closed over the same, as desired.

20 N is a stop or rest formed on or firmly secured to the upper part of the cowl B to support the said shutter or door when opened and turned back upon its hinges, as shown in dotted lines in the drawings.

25 B² is a thumb-screw or set-screw for retaining or securing the cowl B in any position to which it may be adjusted to catch the wind.

In some instances I dispense with the annular recess A* and packing-ring E.

30 Fig. 2 illustrates a modification of my invention, wherein the annular groove D' and packing-ring E' are dispensed with, the groove A* and packing-ring E being retained, and wherein the screw F is provided with left-hand 35 square threads instead of right-hand V-shaped threads, as in Fig. 1. The said screw is, moreover, secured in the cross-bar or cross-piece G by means of the collar F² and nut G² without the aid of screw-threads in the boss G'.

40 G³ is a nut for preventing the accidental removal of the screw F from the boss or nut H'.

When my improved cowl is to be applied to an existing ventilating-pipe, I find it advantageous to provide a flanged ring or annular piece A³, Fig. 2, which is fitted and secured in the existing cowl-coaming or ventilating-pipe A, and is provided with the cross-bar H, and in which is formed the groove or recess A* for the packing-ring E. The said 45 flanged ring A³ then forms, practically, a part of the ventilating-pipe A.

50 My improved cowl can be advantageously employed in combination with ventilating-pipes having floats or valves—such, for example, as those described in the specification of former British Letters Patent granted to me and dated November 29, A. D. 1888, No. 17,422—or with any other suitable ventilating pipes or apertures.

What I claim is—

60 1. A ship's ventilator consisting of a ventilating-pipe A, a cowl B, fitted water-tight to the pipe and having at its upper edge the lugs J, the imperforate shutter or door C, co-extensive with the mouth of the cowl and hinged at its upper edge to the lugs, and a clamp located at the lower edge of the shutter or door for binding the latter water-tight against the edge of the cowl-mouth, substantially as described. 65

70 2. A ship's ventilator consisting of a ventilating-pipe A, a cowl B, fitted water-tight to the pipe, the shutter or door C, hinged at one edge to the cowl coextensive with the mouth thereof and having an annular groove C', containing a packing-ring C² to seat water-tight against the edge of the cowl-mouth, and a clamp carried by the cowl for clamping the shutter or door in its closed position, substantially as described. 75

80 3. A ship's ventilator consisting of a ventilator-pipe A, a cowl B, fitted water-tight to and having a central screw connection F with the ventilating-pipe, the imperforate shutter or door C, coextensive with the mouth of the 85 cowl and hinged at one edge thereto, and a clamp located at one edge of the shutter or door for clamping it water-tight against the edge of the cowl-mouth, substantially as described. 90

4. The combination of a ventilating-pipe A, cowl B, shutter or door C, connecting device or screw F, and recesses A*, D', and C', having fitted therein suitable washers or packing-rings for forming fluid-tight joints between the cowl B, ventilating-pipe A, and shutter or door C, substantially as described. 95

5. The combination of a ventilating-pipe A, flanged ring or annular piece A³, cowl B, shutter or door C, connecting device or screw F, recesses A* C', and washers or packing-rings E C², substantially as described. 100

6. The combination of a ventilating-pipe A, cowl B, shutter or door C, connecting device or screw F, recesses A* D' C', washers or 105 packing rings E, E', and C², fastening device K L, and clamping-screw B², substantially as described.

In testimony whereof I have hereunto signed my name in the presence of two subscribing witnesses. 110

THOMAS UTLEY.
